DEODORANT STICK JAR

John H. Funkey, Timonium, Md., assignor, by mesne assignments, to Pharma-Craft Corp., Batavia, Ill.

Application August 23, 1957, Serial No. 47,486

Term of patent 14 years

(Cl. D58—25)

I claim:

The ornamental design for a deodorant stick jar, as shown.
